UNITED STATES PATENT OFFICE.

ROBERT WALSH, OF PHILADELPHIA, PENNSYLVANIA.

DESIGN FOR A COMBINED SPOOL-STAND AND PINCUSHION.

SPECIFICATION forming part of **Design No. 22,791**, dated **September 19, 1893**.

Application filed **August 24, 1893**, Serial No. **483,985**. Term of patent **7 years**.

To all whom it may concern:

Be it known that I, ROBERT WALSH, a citizen of the United States, residing in Philadelphia, Pennsylvania, have invented a certain new and original Design for a Spool-
Stand and Pincushion, of which the following
is a specification.

My design for a combined spool stand and pin cushion is shown in the accompanying
drawing, which represents a side view of the
same.

The circular base A is mounted upon feet
a and has studs or pins b projecting upward
therefrom at some distance inward from the
edge of the base. From the base rises a
pin-cushion-supporting column B, and sur-

mounting the latter is the outwardly flaring
base D of the cushion F, while above the latter
is a cap f from which projects a stem g
with short arms i projecting laterally there-
from near the upper end.

I claim—

The design for a combined spool stand and
pin cushion, substantially as described and
as shown in the accompanying drawing.

In testimony whereof I have signed my
name to this specification in the presence of
two subscribing witnesses.

ROBERT WALSH.
